UNITED STATES PATENT OFFICE.

WARREN H. TAYLOR, OF STAMFORD, CONNECTICUT, ASSIGNOR TO THE
YALE LOCK MANUFACTURING COMPANY, OF SAME PLACE.

POST-OFFICE LOCK-BOX.

SPECIFICATION forming part of Letters Patent No. 252,708, dated January 24, 1882.

Application filed October 10, 1881. (Model.)

To all whom it may concern:

Be it known that I, WARREN H. TAYLOR, of Stamford, in the county of Fairfield and State of Connecticut, have invented certain new and 5 useful Improvements in Doors for Post-Office Lock-Boxes, of which the following is a specification, reference being had to the accompanying drawings, in which—

Figure 1 is a front elevation of a post-office letter-box embodying my improvement, showing the door closed. Fig. 2 is an inside or rear view of the door detached from the box. Fig. 3 is a vertical section of the door drawn on the line 3 3 of Fig. 2.

15 Ordinarily doors of post-office lock-boxes and the like are made of cast metal, with openings merely for glass.

The object of my invention is to provide a lighter and cheaper door composed of different 20 parts and materials, instead of being of cast metal in one piece. Such a door is also preferable on account of its facility for ornamentation.

My invention consists of an improved door 25 for pigeon-holes, especially of post-offices, made up of a surrounding rim or frame of metal, A, and filled out in front with a plate or panel, B, of other material—such as hard rubber, wood,

paper, or like cheap suitable hard substance—within which to secure ordinary glass panels, 30 C and D, and lock E. Such a door may be either hinged or screwed or otherwise fastened over the end of a pigeon-hole that is provided or not with a metallic frame such as illustrated at F in Fig. 1.

35 The door frame or rim A may be either of stamped or cast metal, and the plate B may be secured within it, after the glass has been put in place in the usual manner, by means of lugs and rivets, as at G, or otherwise, as usual. 40

Having thus described my invention, what I claim as new, and desire to secure by Letters Patent, is—

An improved door for a pigeon-hole, composed of a rim or frame, A, of metal, having 45 in front of it a plate or panel, B, of other material—such as hard rubber, wood, paper, or other like suitable hard substance—substantially as and for the purposes specified.

In testimony whereof I have hereunto subscribed my name this 5th day of October, A. D. 1881.

WARREN H. TAYLOR.
